UNITED STATES PATENT OFFICE.

EDMUND W. HANCOCK, OF NEW YORK, N. Y., ASSIGNOR TO WESTERN ELECTRIC COMPANY, INCORPORATED, OF NEW YORK, N. Y., A CORPORATION OF NEW YORK.

TELEPHONE-EXCHANGE SYSTEM.

Application filed March 21, 1921. Serial No. 454,105.

To all whom it may concern:

Be it known that I, EDMUND W. HANCOCK, a citizen of the United States of America, residing at New York, in the county of 5 New York, State of New York, have invented certain new and useful Improvements in Telephone-Exchange Systems, of which the following is a full, clear, concise, and exact description.

10 This invention relates to telephone systems and more especially to systems in which connections extending through a plurality of offices are established by means of machine switching apparatus located in the different offices involved.

In certain types of interoffice exchange systems calls which are destined for outlying districts are first received at the originating office by an answering operator. The 20 operator is provided with central office register senders and a keyboard at her position. After orally receiving from the calling subscriber the destination of the desired line she makes a record thereof on the 25 keyboard which causes the register sender to take a corresponding setting. With the record of the called line established on the register sender of the originating office it then becomes effective to control automatic 30 switches to select an outgoing trunkline leading to the proper distant mechanical office. At the distant office the incoming trunks extend to automatic selective switches. In 35 order to control the selective operation of the automatic switches in the distant office, register senders are provided thereat similar in function to those at the originating office, except that in the latter case the senders are positioned by means other than an operator's keyboard.

When an interoffice trunk has been selected an idle one of the register senders at the distant office is associated with said trunk. Following this the record of the desired designation, which was first established by the operator on the sender of the originating office, is transferred over the 45 interoffice trunk to cause a corresponding setting of the associated sender, thereby producing the record in the distant office. The second register sender then operates to control the selective switches in the distant office to further extend the connection toward its destination.

50 Where the originating office concerned in

an interoffice connection is full-mechanical in character the calling subscriber causes the setting of the register sender therein by means of an impulse transmitter. The switches at the originating office are operated to select an outgoing trunk, the record is transferred to the distant office sender and the switches of the distant offices are operated in the same manner as above outlined.

Inasmuch as the number of register senders, provided at the distant or tandem office for serving the trunks incoming from an originating office, must necessarily be limited it may frequently occur that all of 60 these senders will be simultaneously busy. With all senders busy a connection extended over one of the interoffice trunks to the distant office would receive no attention, since there is no sender available to take the 65 transferred record and to control the further establishment of the connection. Consequently, while there may be idle trunks at the time in the interoffice group, the selection of one of these trunks by the switches 70 at the originating office is of no avail owing to the fact that the busy condition of all senders at the distant office prohibits the further extension of the call.

With the foregoing facts in mind, the object of the present invention is the provision of means controlled jointly by the register senders in the second office for rendering all trunks of the group incoming 75 from the first office non-selectable at the 80 first office.

A feature of the invention relates to the provision of a plurality of groups of senders serving respectively a plurality of groups of interoffice trunks, and a common group of 85 senders serving all trunks, together with means whereby all trunks of any group are rendered non-selectable at their outgoing end when all senders individual to that group and all of the common senders at the 90 incoming end of said trunks are simultaneously busy.

Such other and further features as are contemplated by the present invention will 95 become more clearly understood from a consideration of the following description and the appended claims.

Figs. 1 and 2 of the drawing when taken in order illustrate an interoffice telephone system wherein the subject matter involving 100

the principles of the invention is shown in sufficient detail to enable a thorough comprehension thereof. Fig. 1 shows a first or originating office with one of the subscriber's lines terminating therein before an operator's position and an operator's cord circuit, one end of which terminates in a plug and the other end in the movable brushes of a selector switch. This figure also illustrates a plurality of trunk lines accessible to the selector switch which lead to a distant office. Furthermore, this figure illustrates equipment whereby the outgoing trunk lines may be rendered non-selectable to the selector switches such as the one shown. Fig. 2 illustrates a distant office at which the interoffice trunks incoming from the originating office terminate in the movable brushes of selector switches. This figure also discloses in a diagrammatic manner a plurality of register senders which are arranged to be associated with the incoming trunk lines together with sender selector switches for accomplishing this purpose.

To avoid the unnecessary details in the showing of the selector switches, the register sender and the operator's equipment at the originating office in Fig. 1, these various elements have been illustrated in schematic form. The selector switch, known as the district selector, is of the well-known power-driven panel type such as the switch shown and described in detail in the patent to Craft and Reynolds 1,123,696, issued January 5, 1915. This switch consists of a vertical brush shaft 110 carrying a plurality of sets of brushes, two of which are shown at 111 and 112. All of the brushes carried on the shaft 110 are connected in multiple to the operator's cord circuit, the other end of which terminates in the plug 102 adapted to be inserted in the jack 101 of a calling subscriber's line.

For propelling the brush shaft 110 an up-drive magnet 108 is arranged to press the depending portion of said shaft against the constantly rotating drum 131. The down-drive power magnet 132, when energized, presses the depending portion of said shaft against a drum 133 rotating constantly in the opposite direction to cause the downward or restoring movement of the switch.

The register sender schematically shown within the dotted rectangle 105, a plurality of which are provided at the operator's position, serves as a medium for receiving the record of the desired destination and to control in accordance with this record the movement of the district selector switch shown in Fig. 1 to select a trunk leading to the desired distant office in the case of an interoffice call and also to exercise the necessary control of the apparatus beyond to properly direct a further establishment of the connection. This sender comprises a plurality

of registers, an operator's keyboard and the other usual elements. In the schematic illustration, however, only the stepping relay 106 included in the fundamental circuit and one of the counting relays 107 are shown.

The sequence switch 103, which is of the usual type, serves by means of its several contacts (not shown) to control the necessary change-over functions involved in the operation of the district selector.

The terminal bank of the selector switch is divided into a plurality of groups, one for each of the several sets of brushes carried on the shaft 110. Two of these groups 113 and 114 are shown. The group 114 consists of the terminals of a plurality of trunk lines outgoing to the distant office shown in Fig. 2. One of these trunks 115, 116 and 117 is shown completely, the talking conductors 115 and 116 thereof extending to the distant office and there terminating in the brushes of the selector switch 200. The third or test conductor 117 terminates in the contact of relay 126. The terminals of three other trunks are shown for the group 114, the test conductors 134, 135 and 136 of these three trunks terminating in the contacts of relays 126 and 125. Although not shown it is understood, of course, that any number of trunks desirable may be included in the group 114 and that these trunks lead to the distant office and terminate in the brushes of selector switches similar to switch 200.

In a similar manner the group 113 is shown as consisting of the terminals of four trunk lines, one of which, 118, 119, extends to the distant office and terminates in the brushes 201 of a selector switch. The test conductors 120, 137, 138 and 139 terminate in the contact of relays 129 and 128. Similarly, the group 113 may comprise as many trunks as desired. Also the other trunk groups served by brush sets (not shown) may have talking conductors leading to the distant office and test conductors which terminate in the contacts of relays 125, 126, 127, 128, 129 and 130.

For the purpose of the present invention it will be considered that all of the interoffice trunks outgoing from the terminal bank of the district selector switches are divided into two groups regardless of how they may appear in the smaller brush groups. For example, a certain number of brush groups, one of which is the brush group 114, may comprise the first major group of outgoing trunks. The second major group then will consist of the remaining brush groups of which the brush group 113 is one. The make busy equipment shown in the lower right-hand corner of Fig. 1 is accordingly divided into two parts. The first part consists of relays 121, 123, 125, 126, and 127 individual to the first major group of outgoing trunks and serves

under the proper conditions to render said trunks non-selectable to the district switches. The second part of the make busy equipment consisting of the relays 122, 124, 128, 5 129 and 130 is individual to the second major group of outgoing trunks for an identical purpose.

Inasmuch as only two interoffice trunks 115, 116 and 118, 119 are fully shown, only 10 the two corresponding selector switches 200 and 201 in the second office are illustrated. It is understood, of course, that for each 15 of the other incoming trunk lines there is provided an individual selector switch similar to switches 200 and 201. Each selector switch at the distant office has an individual sender selector which serves to associate its incoming trunk with an idle one of a plurality of register senders. The 20 sender selector individual to the trunk 115, 116 of the selector switch 200 is illustrated by the brushes 202, 203 and 204. The brushes of the sender selector switch have access through their terminals to a group 25 of register senders which serve the first major group of interoffice trunks including trunk 115, 116. The three register senders 210, 215 and 220 shown within the small broken rectangles at the right of Fig. 2 30 belong to the group of senders which normally serve the first major group of incoming trunks. Obviously, there may be as many senders in this group as the traffic requirements justify.

35 The sender selector switch which is individual to the interoffice trunk 118, 119 and the selector switch 201 is represented by the brushes 205, 206 and 207. These brushes have access through their terminals 40 to a second group of register senders which are individual to the second major group of interoffice trunks containing the trunk 118, 119. Likewise, only three of the register senders 225, 230 and 235 in this second 45 group are illustrated. Each of the incoming trunks of the first major group is provided with a sender selector switch having brushes similar to brushes 202, 203 and 204 which have access to terminals connected in multiple to the conductors shown 50 leading to the register senders 210, 215 and 220 of the first group, that is to say, all of the sender selectors associated with the first major group of incoming trunks 55 have their terminals connected in multiple, whereby anyone may select any idle register sender of the first group of senders. The same is true as regards the register senders provided for the incoming trunks 60 of the second major group, whereby any one of these may select any idle sender in the second group of senders.

In addition to the two groups of individual senders already described there is 65 provided a third or common group of reg-

ister senders at the distant office, two of which are shown at 240 and 245. The senders of this third group are arranged in common to both the major groups of incoming trunks and may be chosen by the sender selector switches associated with the trunks of either incoming group. For this purpose the conductors which lead to the various elements of the register senders 240 and 245 are multiplied to the corresponding terminals in the sender selector switches associated with both groups of incoming trunks.

It has not been considered necessary to show in detail the complicated structure of the register senders. Instead, each sender is illustrated by a few of its characteristic elements. For example, the sequence switches 211, 216, 221, 226, 231, 236, 241 and 246 are individual respectively to the several senders and serve the well-known purpose of controlling their operations. Relays 212, 217, 222, 227, 232, 237, 242 and 247 are the respective stepping relays included in the fundamental switch controlling circuits. Relays 213, 218, 223, 228, 233, 238, 243 and 248 are the well-known O' counting relays of the respective senders which serve to sever the fundamental circuit at the completion of each selective movement of the switch and of succeeding switches (not shown). The purpose of relays 214, 219, 224, etc., one of which is provided for each register sender, will become apparent from the following description.

The selector switches diagrammatically illustrated at 200 and 201 are also switches of the power-driven panel type such as shown in the patent to Craft and Reynolds 1,123,696, issued January 5, 1915. For a complete description of the detailed construction and operation of the selector switches, register senders and other circuits represented, in Figs. 1 and 2 of this disclosure, reference is made to the patent to E. W. Hancock, No. 1,439,735, granted December 26, 1922.

When the calling subscriber of a line such as line 100 initiates a call, a line lamp (not shown) is lighted before the operator in the central office. In response to the signal the operator inserts the plug 102 of an idle cord circuit in the jack 101 of the calling line. In the manner described in the above mentioned application the insertion of the plug in the jack automatically causes an idle register sender 105 to be associated with the cord circuit and also causes the operator's telephone set (not shown) to be telephonically connected to the calling line. The operator orally receives the designation of the desired line from the calling subscriber and sets up the record thereof on her keyboard, which in turn, causes the registers of the sender to assume their corresponding setting. Thereafter, the fundamental circuit

is closed, relay 104 energized, and the circuit of the up-drive power magnet 108 is closed to cause the upward movement of the brush shaft 110, first, to select the proper one 5 of the several sets of brushes and then to drive the selected set of brushes over the terminals of the group to which it has access to choose an idle trunk outgoing to the desired distant office. It will be assumed first that 10 the brush set 111 is chosen which has access to the first major group of outgoing trunks. It will further be assumed that some one of the register senders 210, 215 and 220 of the group of senders in the distant office individual to the first major group of inter-office trunks is idle at the time. Following 15 the selection by brushes 111 of an outgoing trunk in the first major group, such as trunk 115, 116, the sender selector switch, 202, 203, 20 204 individual to trunk 115, 116 is set in operation to select an idle register sender. If the second sender 215 is idle the brushes 202, 203 and 204 stop in engagement with the second set of terminals 254, 255 and 256 and 25 this sender is seized and associated with the incoming trunk 115, 116.

The record originally registered by means 30 of the operator's keyboard at the sender 105 in the originating office may now be transferred over the trunk 115, 116 and reproduced on the registers (not shown) of the selected idle register sender 215 in the distant office. The record having thus been transferred 35 the sender 215 becomes effective to control, over its fundamental circuit, the selector switch 200 and succeeding switches to extend the connection to its destination. During the period that the sender 215 is engaged, a ground potential is extended from 40 the selector switch 200 as by means of a relay 250, over the brush 202 of the sender selector, terminal 254, conductor 257, winding of relay 219 to battery and ground. Relay 45 219 is energized and serves thereby to indicate that the register sender is busy.

Should all of the register senders of the group individual to the first major group of interoffice trunks be busy when a connection is extended to the distant office by way 50 of one of said trunks, such as trunk 115, 116, then the brushes 202, 203 and 204 of the sender selector are advanced to test the terminals representing the senders 240, 245, etc., of the common group of senders. Provided the first of these, sender 240, is idle, the brushes 202, 203 and 204 stop on the terminals 258, 259 and 260 and the sender 55 240 is seized and associated with the trunk 115, 116. After the conversation has been completed the connection may be restored in any well-known manner.

Had the district selector switch in the originating office been operated to choose its brush set 112 which has access to the trunks 60 of groups 113, the connection would then be

extended over an interoffice trunk of the second major group, such as trunk 118, 119, which terminates in the brushes of the switch 201 at the distant office. In this case the sender selector switch 205, 206 and 207 is set in operation to test the condition of the register senders 225, 230 and 235 of the second group of senders individual to the second major group of interoffice trunks. If idle, one of these senders is seized and associated with the incoming trunk for the same purpose already explained. If, however, none of these senders is idle at the time, the sender selector switch 205, 206, 207 70 75 80 searches for an idle sender in the common group.

It will now be considered that the establishment of a connection is attempted over the first major group of trunks 114 at a time when all of the register senders 210, 215 and 220 individual thereto and also all of the common senders 240 and 245 are busy. Since all senders available to any of the trunks in the first major group are simultaneously busy, it would be useless for the 90 95 100 district selector switch 110 to seize one of these trunks and extend the connection to the distant office. Consequently, this unnecessary operation is avoided in a manner about to be discussed.

Inasmuch as all of the senders 210, 215, 220, 240 and 245 are simultaneously busy, their individual relays 214, 219, 224, 244, 249 are energized. A circuit is therefore established from battery through the winding of relay 208, armatures and contacts of relays 214, 219, 224, 244 and 249 in series to ground. Relay 208 energizing in this circuit establishes a circuit from battery through its armature and contact, conductor 252 leading to the originating office, thence through the winding of relay 121 to ground. Relay 121 completes a circuit at its armature and contact for relay 123. Relay 123 at its armatures and contacts closes circuits for the relays 125, 126 and 127. Relays 125, 126 and 127 become energized and apply ground potential to the test terminals of all trunks in the first major group by way of conductors 117, 134, 135 and 136. Hence, when the district selector switch 110 is operated to drive its brush set 111 over the terminals of the group 114, all of these terminals will be found artificially busy, and the connection will progress no further.

In a similar manner if a connection is attempted by way of the second major group of office trunks 113 at a time when all of the senders serving such second major group together with all of the common senders are busy, the trunks of this group are found non-selectable and the establishment of the connection is arrested. Since the senders 225, 230, 235, 240 and 245 are simultaneously busy, their relays 229, 234, 239, etc. are operated and a circuit is closed from battery 110 115 120 125 130

through the winding of relay 209, armatures and contacts of relays 229, 234, 239, 244 and 249 to ground. Relay 209 is operated and completes a circuit from battery through its 5 armature and contact, conductor 253 leading to the originating office, through the winding of relay 122 to ground. Relay 122 operates and completes a circuit for relay 124. Relay 124 at its armatures and contacts closes 10 circuits for relays 128, 129 and 130. These relays are energized and apply ground potential over conductors 120, 137, 138 and 139 to the test terminals of all trunks in the second major group 113. Consequently, 15 when the district selector switch 110 is operated, it will find its trunks non-selectable, and further extension of the attempted connection will be prohibited.

So long as all register senders of either individual group at the distant office together with all senders of the common group remain busy, the corresponding group of interoffice trunk lines are held non-selectable, as above explained, to the district switches in the originating office. Immediately that one 25 of these senders is released and becomes idle, the particular one of the relays 214, 219, 224, etc. which is individual to the released sender becomes deenergized and opens the 30 series circuit for either relay 208 or relay 209 as the case may be. The deenergization of relay 208, for example, removes battery potential from the interoffice cable conductor 252 permitting relay 121 in the originating office to retract its armature. Relay 121 opens the circuit of relay 123, which in turn, breaks the circuits of relays 125, 126, 127, etc. These relays all retract their armatures 35 simultaneously and remove the artificial busy condition from the trunks of the first major group 114, whereby the district selector switches may select any trunk in such group which is not busy by reason of a previously established connection.

40 Although the invention has been illustrated in this disclosure as embodied in a semi-automatic system involving the use of operator's equipment, it should be understood that no such limitation is necessary. 45 The trunk groups, which are rendered busy under certain conditions to avoid the useless extension of connections, may as well be selected by full automatic apparatus controlled directly from the calling subscriber's 50 substation. Moreover, it is not essential to the principle of the invention that the same be shown in connection with the interoffice 55 trunk groups. It is applicable to trunk groups interconnecting successive switching 60 stages of one and the same central office.

What is claimed is:

1. In a telephone system, a trunk line, switching means for selecting said trunk to extend a connection thereover, a second 65 switching means for further extending said

connection, a plurality of register senders for controlling said second switching means, and means for rendering said trunk non-selectable to said first switching means when all of the register senders are simultaneously 70 busy.

2. In a telephone system, a trunk line, switching means for selecting said trunk to extend a connection thereover, a second switching means for further extending said 75 connection, a plurality of register senders for controlling said second switching means, and means controlled jointly by the register senders when all of said senders are simultaneously busy for rendering said trunk non-selectable to said first switching means.

3. In a telephone system, a trunk line, switching means for selecting said trunk to extend a connection thereover, a second switching means for further extending said 85 connection, a plurality of register senders for controlling said second switching means, means for associating an idle one of the register senders with said trunk, and means for rendering said trunk non-selectable to said 90 first switching means when all of the register senders are simultaneously busy.

4. In a telephone system, a group of trunks, automatic switches, switching means for extending connections over said trunks to 95 the automatic switches, a plurality of register senders for controlling the automatic switches to further extend said connections, means for associating the register senders with said trunks, and means for rendering 100 the trunks of said group non-selectable to said switching means when all of said register senders are simultaneously busy.

5. In a telephone system, a group of trunks, automatic switches, switching means 105 for extending connections over said trunks to the automatic switches, a plurality of register senders for controlling the automatic switches to further extend said connections, means individual to each trunk for associating 110 an idle register sender with such trunks, and means for rendering the trunks of said group non-selectable to said switching means when all of said register senders are simultaneously busy.

6. In a telephone system, a plurality of automatic switches, a group of trunks each of which leads to one of said switches, switching means for selecting said trunks to extend connections to said automatic 120 switches, a plurality of register senders for controlling the automatic switches to further extend said connections, means for associating the register senders with said trunks, and means for rendering the trunks 125 of said group non-selectable to said switching means when all of said register senders are simultaneously busy.

7. In a telephone system, a group of trunks, automatic switches, switching means 130

- for extending connections over said trunks to the automatic switches, a plurality of register senders for controlling the automatic switches to further extend said connections, means for associating the register senders with said trunks, means including an element in each of said senders for closing a circuit when all of said senders are simultaneously busy, and means responsive to the closure of such circuit for rendering the trunks of said group non-selectable to said switching means.
8. In a telephone system, a group of trunks, automatic switches, switching means for extending connections over said trunks to the automatic switches, a first and a second group of register senders for controlling the automatic switches to further extend said connections, means for associating a register sender of the first group when one of such senders is idle and for associating a register sender of the second group when all senders of said first group are busy with said trunks, and means for rendering the trunks of said trunk group non-selectable to said switching means when all register senders of both groups of register senders are simultaneously busy.
9. In a telephone system, a plurality of groups of trunks, automatic switches, switching means for extending connections over said trunks to the automatic switches, a plurality of groups of register senders, one for each group of trunks, a group of register senders common to all groups of trunks, said senders serving to control the automatic switches to further extend said connections, means for associating said senders with said trunks, and means operative when all senders of any group together with all senders of said common group are simultaneously busy for rendering the trunks of the corresponding group of trunks non-selectable to said switching means.
10. In a telephone system, a plurality of groups of trunks, automatic switches, switching means for extending connections over said trunks to the automatic switches, a plurality of groups of register senders, one for each group of trunks, a group of register senders common to all groups of trunks, said senders serving to control the automatic switches to further extend said connections, means for associating said senders with said trunks, and means operative when all senders of any group together with all senders of said common group are simultaneously busy for rendering the trunks of the corresponding group of trunks non-selectable to said switching means.
11. In a telephone system, a trunk line, a switch for selecting said trunk to extend a connection thereover, a second switch for further extending said connection, a plurality of controlling senders for governing said second switch, and means for rendering said trunk busy to said first switch when all of said senders are simultaneously busy.

In witness whereof, I hereunto subscribe my name this 18th day of March A. D., 1921.

EDMUND W. HANCOCK.
